UNITED STATES PATENT OFFICE.

LINCOLN BURNHAM, OF URBANA, OHIO.

GAS-ENGINE STARTER.

No. 903,269.

Specification of Letters Patent.

Patented Nov. 10, 1908.

Application filed August 3, 1908. Serial No. 446,639.

To all whom it may concern:

Be it known that I, LINCOLN BURNHAM, a citizen of the United States, residing at Urbana, in the county of Champaign and State of Ohio, have invented certain new and useful Improvements in Gas-Engine Starters, of which the following is a specification.

My invention relates to the improvement of gas engine starters, and the objects of my invention are to provide a simple and effective gas or gasoline engine starting mechanism of improved construction and arrangement of parts; to provide improved means for placing the spring motor under tension while the starting mechanism is out of gear with the crank shaft, and to produce other improvements the details of which will be more fully pointed out hereinafter. These objects I accomplish in the manner illustrated in the accompanying drawing, in which:

Figure 1 is a side elevation of my improved mechanism, Fig. 2 is a plan view, Fig. 3 is an enlarged face view of the spring casing showing a portion of the casing broken away for the purpose of clearness in illustration, and, Fig. 4 is a detail sectional view on line $x-x$ of Fig. 3.

Similar numerals refer to similar parts throughout the several views.

1 represents the usual crank shaft of a gas or gasoline engine, on which is carried the usual fly wheel 2 and a gear wheel 3. 4 represents a counter shaft which may be suitably journaled in the framework of an automobile or other engine frame and which is parallel with the shaft 1. Upon the shaft 4 is carried a ratchet wheel 5 and upon the shaft 1 is mounted loosely and eccentrically one end of a pawl bar 6, the outer end of the latter normally engaging a tooth of the ratchet wheel 5. Journaled upon the shaft 4 is the central portion of a casing 7 and within this casing is contained a coiled spring 8, the inner end of said spring being affixed to the shaft 4 and the outer end thereof being affixed to a transverse casing pin 7^a.

As indicated at 9, the outer side of the casing about the shaft 4 is provided with a clutch member which is adapted to engage a clutch member 10 which projects from the inner face of a gear wheel 11 which is loosely mounted upon the shaft 4. This gear wheel is formed with a grooved outwardly projecting hub 11^a with which engages opposing pins carried by the arms of a bifurcated bell

crank lever 12, the outer end of which is provided with suitable means for swinging said bell crank and thereby moving the gear wheel 11 inward or outward on its shaft. 60

13 represents a bar which has its inner end pivoted as indicated at 14 to one face of the casing 7 at a point between the center and periphery thereof. With the outer side of this bar is connected the lower portion of a 65 plate or disk segment 15 which has its outer curved end portion projecting beyond the periphery of the casing 7. In the underside of this outwardly projecting portion of the segment 15 and in the underside of the corresponding portion of the bar 13 is formed a recess or notch 16. With the bar 13 between its pivot point and the outer end of the bar is connected or formed the pin 7^a, the end portions of which extend through opposing curved slotted openings 17 in opposite sides of the casing 7, one of these openings being indicated in dotted lines in Fig. 3 of the drawing. 70

On the inner side of the pivot 14 of the bar 13 the casing is provided with a projecting pin 18 about which is coiled the inner end portion of a spring 19, said spring having an outwardly extending portion which engages an opening in the segment 15 over the bar 13 80 and tends to normally hold the latter downward in the position indicated in Fig. 3. Above the segment 15, I secure to one face of the casing 7 a radially arranged bar 20, the outer end portion of which projects beyond the periphery of the casing 7 and is provided on its underside with a recess or notch 21. 85

Slidably mounted in suitable bearings 22 on a convenient frame piece 23 is a horizontal 95 pin or bolt 24, the inner end of the latter being adapted, as shown in the drawing, to engage the notch or recess 16 of the bar and segment 13 and 15. The outer end of the pin or bolt 24 has pivotally connected therewith a horizontal bar 25 which is pivoted intermediate of its ends as shown at 26 to the frame member 23. Beyond its pivot point the end of the bar 25 engages the peripheral groove 11^b of the hub 11^a. Below the 100 outer end portion of the pawl 6 is provided a laterally extending pin 27 which projects from the casing 7. 105

In the drawing, I have shown the spring 8 unwound or out of tension, the clutch member 10 out of engagement with the clutch member 9, the bolt or pin 24 in engagement 110

with the notch or recess 16 and the pawl 6 in engagement with one of the teeth or notches of the ratchet wheel 5.

The moving parts of the engine being in motion and the crank shaft 1 being thus rotated, it will be understood that the eccentrically connected pawl bar 6 will have imparted thereto an outward and inward reciprocating movement which will result in alternately moving the ratchet wheel in the direction of the arrow in Fig. 3 and dropping the pawl arm downward to engage a new tooth of said wheel, thereby causing an interrupted rotation of the ratchet wheel and the shaft 4 and a gradual winding or tightening action of the spring 8 about said shaft. This winding action of the spring owing to its connection with the casing 7, results in a gradual movement of the casing in the direction of the dotted arrow in Fig. 3. This movement of the casing as will readily be understood, will be imparted to the inner end portion of the bar 13 and segment 15, the outer ends thereof being retained against downward movement by contact with the bolt or pin 24. It will be understood, however, that as the pin 7^a is thus carried to the opposite ends of the slots 17 and the bar 13 turned on its pivot point, the bolt or rod 24 will eventually move out of engagement with the recess or notch 16 owing to the inward movement of the outer curved end portion of the segment. The bolt or pin 24 being thus released, is in turn engaged by the notch or recess 21 of the bar 20. In the partial rotary movement of the casing heretofore described, it is obvious that the casing pin 27 will eventually come into contact with the underside of the inner end portion of the pawl bar 6, resulting when sufficient tension has been imparted to the spring, in a disengagement of said pawl bar from the teeth of the ratchet wheel 5. The parts being in this position, it will be understood that the unwinding of the spring will be prevented by the engagement of the pin or bolt 24 with the bar 20. The engine having been stopped and it being desired to impart to the crank shaft the usual preliminary starting movement, the bell crank 12 is so moved on its pivot as to throw the clutch member 10 of the gear wheel 11 into unlocking engagement with the clutch member 9 of the spring casing. In this operation, it is obvious that the bar 25 will be caused to swing on its pivot 26, with the result that the pin or bolt 24 will be drawn out of engagement with the notch of the bar 20, thereby permitting the previously tensioned spring to act to rotate the shaft 4, gear wheel 11 and the gear wheel 3 with which said wheel 11 engages. In this manner, the desired preliminary rotary movement ordinarily necessary in starting gas or gasoline engines is imparted to the crank shaft. It is obvious that a reverse

movement of the bell crank 12 will result in restoring the parts to the position indicated in Fig. 2 of the drawing.

From the construction and operation described, it will be observed that the means which I employ in carrying out my invention are simple of construction and operation and positive in their action.

What I claim, is:

1. In a gas engine starting mechanism, the combination with an engine crank shaft, and a gear wheel thereon, of a counter shaft, a ratchet wheel carried on the counter shaft, a casing loose on said counter shaft, a coiled spring within the casing having one end connected with said counter shaft and its remaining end with the casing, a gear wheel loose on the counter shaft adapted to mesh with the crank shaft gear wheel, a pawl bar eccentrically mounted on the crank shaft and normally projecting within the path of the teeth of said ratchet wheel, and means for engaging and disengaging the spring case and the counter shaft gear wheel.

2. In a gas engine starting mechanism, the combination with the engine crank shaft, and a gear wheel thereon, of a counter shaft, a spring casing loose on said counter shaft and having a clutch projection, a coiled spring in the casing one end of which is connected to the counter shaft and the remaining end to the casing, an arm pivoted to the casing and projecting beyond the periphery of the latter, said arm having an underside notch in its outer portion, a bar projecting from the casing and also having an underside notch in its projecting portion, a slidable bolt adapted to project within the path of said arm and bar notched portions, a gear wheel loose on the counter shaft and having a clutch projection, a pivoted arm connecting said slidable bolt and gear wheel, and means connected with the crank shaft for imparting rotary motion to the counter shaft to wind said spring, and means for automatically disconnecting said winding means.

3. In a gas engine starting mechanism, the combination with a crank shaft, and a gear wheel carried thereby, of a counter shaft, a ratchet wheel carried thereon, a casing loose on said counter shaft, and a coiled spring within the casing, said spring having one end connected with the counter shaft and the remaining end with the casing, a clutch projection on the casing, a gear wheel slidable on said counter shaft and meshing with the crank shaft gear wheel, said counter shaft gear wheel having a clutch projection, a pivoted arm on one side of the casing and a fixed arm above said pivoted arm, said arms having projecting notched portions, a slidable bolt adapted to be projected into position to engage either of said notches, and means whereby a sliding movement of the counter shaft gear wheel limits an opposite sliding movement of said

slidable bolt, a pawl bar eccentrically mounted on the crank shaft and having its outer end normally engaging said ratchet wheel, and means for automatically releasing said pawl bar from engagement with said ratchet wheel when desirable tension has been imparted to the spring.

In testimony whereof I affix my signature in presence of two witnesses.

LINCOLN BURNHAM.
